E. J. BLAKE

GOVERNOR

Filed Jan. 27, 1919

Patented Oct. 27, 1925.

1,559,065

UNITED STATES PATENT OFFICE.

ELI J. BLAKE, OF BUFFALO, NEW YORK, ASSIGNOR, BY MESNE ASSIGNMENTS, TO THE GOULD COUPLER COMPANY, A CORPORATION OF MARYLAND.

GOVERNOR.

Application filed January 27, 1919. Serial No. 273,225.

To all whom it may concern:

Be it known that I, ELI J. BLAKE, a citizen of the United States, and residing at Buffalo, county of Erie, State of New York, have invented certain new and useful Improvements in Governors, of which the following is a specification.

My invention relates to governors, and particularly to a centrifugal governor for steam turbines.

It was my object to design a governor of the above character which could be applied directly to the end of a power shaft and as an extension thereof, that is, to be applied so that the governor would act in alignment with the shaft, and also to eliminate the element of friction in such an arrangement.

The governor described below and shown in the accompanying drawing is a result of my endeavors to the above end.

Fig. 1 of the drawing shows a longitudinal section of the governor together with a portion of the end of the power shaft to which it is applied.

Fig. 2 shows a somewhat simpler form of governor.

A member 1 is suitably fastened onto the end of the shaft 2. In Fig. 1 the member 1 is screwed onto the shaft and is held in place by cotter-pin 3. The member 1 is generally cup-shaped. At the mouth of the cup is placed a disk 4 held in place by means of bolts 5. The interior of the mouth of the cup is screw-threaded, and screwed into this part of the cup is a spring seat member 6, which itself is chambered interiorly and which is held in adjusted position in the cup member 1 by the disk 4, the latter being apertured to receive the member 6 as shown in Fig. 1. Mounted in axial alignment with the shaft 2 is a valve member comprising a valve shaft 7 having a stiff coiled spring 7^a attached to its inner end, the other end of the spring 7^a having spindle 7^b secured thereto, whereby a valve spindle is provided which is flexible at 7^a. Surrounding the member 7^b is a disk-shaped spring seat member 8 with an extension 9 extending into an opening in the member 1 and having a sliding engagement therewith and so arranged that it has a relative longitudinal motion with respect to the member 1 and the shaft 2. This member 8 is chambered on the side opposite the shaft 2.

55 Mounted around the member 7^a and within

the chambered portions of the members 6 and 8 is a coil spring 10. Mounted in the member 1 are centrifugal elements one of which is shown at 11. These elements are crumpled at 12 and the curved ends thereof bear against the member 8. The member 7^b is fixed with relation to the member 8. Surrounding the parts above described is a casing 13, and this casing at its outer end is provided with a steam inlet passage 14 and an exhaust 15, and ports 16 and 17, forming a communication between the passages 14 and 15. The housing 13 is provided with an opening to the outside atmosphere in alignment with the passages 16 and 17 and this opening is normally closed by a screw plug as shown in Fig. 1. The passage 15 may lead directly to the turbine or to a throttle valve for controlling the main steam supply. On the end of the valve member 7 is a valve 18 which is connected with the other part of the member 7 by means of a reduced neck portion 19. The valve 18 is arranged to pass inside the port 16, and a part of the member 7 likewise passes within the port 17, for the purpose of controlling the flow of steam through these two ports.

Surrounding the member 7 and carried by the casing 13 is a steam packing 20 which prevents the leakage of steam from the chamber 21 into the governor. This packing is also so arranged as to permit of a relatively free motion of the member 7. Surrounding the casing 13 is a band 22 of non-corrodible metal, the same being held in place by means of the bolts 23.

The casing 13 may be supported in any suitable manner but in the arrangement shown is supported by a flange portion 24 which is held against a supporting member 25 by means of bolts 26. Between the flange 24 and the member 25 is a gasket 27.

The operation of the device of Fig. 1 is as follows:

When the machine is at rest, the parts assume the position shown in the drawing. As the speed increases, it finally reaches a point where the centrifugal force causes the straight ends of the member 11 to fly outwardly against the action of the spring 10. This action causes the curved ends of the centrifugal members 11 to be moved in a clockwise direction thereby forcing the member 8 together with the members 7^b, 7^a 110

and 7 to the left and reducing the available opening through the ports 16 and 17 in the steam supply. The parts are so adjusted that this movement of the member 7 will not take place until the machine has reached and slightly exceeded its normal speed. Upon the machine attaining a speed materially above the normal speed, the valves and the member 7 are moved to the left to reduce the steam supply, thereby reducing the speed. As the speed is reduced, the valves automatically recede, thereby giving a substantially constant speed to the power shaft 2.

15 From the above construction, it will be noted that all of the governor mechanism, including the member 7 and the valves, revolves or rotates at substantially the same speed as the shaft 2. The member 1, of course, rotates at the exact speed of the shaft 2 and ordinarily the members 7 and 8 would likewise rotate at the same speed as the shaft 2. However, it will be noted that these parts are driven only by the friction between the spring 10 and the member 6 at one end and the spring 10 and the member 8 at the other end. Unless, therefore, the friction between the packing 20 and the member 7 is greater than the friction between the parts above mentioned, the member 7 will rotate at the same speed as the shaft 2. The mechanism is designed and adjusted so that the speed of rotation of the member 7 will be the same as that of the shaft 2.

30 Referring to Fig. 2, 2 is a shaft on which is mounted a member 28 which rotates with the shaft 2. Mounted on the member 28 are centrifugal members 29. These members have projections 30 which are united at 31. Bearing against one side of the union 31 is a spring 32 which tends to hold the members 29 in the position shown. The turbine housing 33 (shown only in part) has in line with the shaft 2 a steam passage 34. This passage opens at 35 to the atmosphere and is connected by the pipe 36 to any suitable throttle valve. Placed in the passage 35 is a slide valve 37. This valve 37 is connected with the union 31 by means of a flexible driving shaft 38.

45 The pilot valve, above described, may be connected with any form of control valve,

the arrangement being such that as the members 29 fly outward the control valve 55 will so operate as to decrease the steam supply to the turbine nozzle, and as the members 29 take their normal position as shown, the normal supply will be furnished to the turbine. By this arrangement the 60 turbine speed will be controlled within certain limits, which limits will be determined by the arrangement of the various parts.

From the foregoing description taken in connection with the operation of the device 65 of Fig. 1, I believe that the operation of the device of Fig. 2 will be perfectly apparent and therefore need not be set out in detail.

In both modifications shown in the drawings there is a small clearance between the valves and their ports to permit of easy operation and also to allow for a slight variation from true alignment. The flexible connection 38 in Fig. 2 would permit in that case 75 of a greater variation from alignment without difficulty in operation.

Obviously many changes in detail may be made without in any way departing from the spirit of my invention, and I therefore 80 do not desire to be limited to the exact detail shown and described.

Having fully described my invention, what I claim as new and desire to secure by Letters Patent is:

85 In a governor mechanism the combination of a rotating shaft, a stationary frame having bearings for said shaft, a frame secured on the end of said shaft, and rotating therewith, centrifugally operated members pivoted on said frame, a stationary housing secured to said first frame and surrounding said centrifugal members, said housing having a passage in line with said shaft, a valve member rotating coaxially with said shaft and flexibly connected with respect thereto and adapted to be moved axially of the shaft by said centrifugal members to regulate the flow of fluid through said passage, and a 95 coiled spring coaxially arranged with said shaft and opposing the action of said centrifugal members.

100 In testimony whereof, I have signed my name to this specification.

ELI J. BLAKE.
